Primary Examiner—Michelle Clement*(74) Attorney, Agent, or Firm*—Nelson Mullins Riley & Scarborough, LLP(57) **CLAIM**

The ornamental design for a container clip, as shown and described.

DESCRIPTION

FIG. 1 is a perspective view of a container clip embodying the design of the present invention;

FIG. 2 is a front elevational view of the container clip illustrated in FIG. 1;

FIG. 3 is a rear elevational view of the container clip illustrated in FIG. 1;

FIG. 4 is a left side elevational view of the container clip illustrated in FIG. 1;

FIG. 5 is a right side elevational view of the container clip illustrated in FIG. 1;

FIG. 6 is a top view of the container clip illustrated in FIG. 1; and,

FIG. 7 is a bottom view of the container clip illustrated in FIG. 1.

1 Claim, 3 Drawing Sheets

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.
